UNITED STATES PATENT OFFICE.

VENNING D. SIMONS, OF CHICAGO, ILLINOIS.

APPARATUS FOR THE MANUFACTURE OF PAPER.

Application filed September 16, 1921. Serial No. 501,113.

This invention relates to an improved process and apparatus for the manufacture of paper and its purpose is to provide means for increasing the speed and efficiency of paper manufacturing operations.

An important object of the invention is to provide means for causing pulp stock to flow positively in an angular path adjacent to the mold on which the paper web is formed. A further object is to provide an apparatus of the cylindrical type carrying an endless wire belt and comprising means for moving the pulp stock positively in the same direction that the wire belt travels. Still another object is to provide a simultaneous movement of the paper mold and pulp stock together with means for regulating the relative speeds of these movements. A further object is to provide a movable paper mold in combination with means independent of the pulp and stock supply for effecting a local circulation of the pulp stock through the mold containing vessel or vat. Other objects relate to various features of construction and arrangement which will appear more fully hereinafter.

The nature of the invention will be understood from the following specification taken with the accompanying drawings in which one embodiment is illustrated.

In the drawings—

Figure 1 shows a side elevation of the apparatus;

Fig. 2 shows an end elevation of the apparatus, parts of the interior construction illustrated by dotted lines.

The invention comprises a vessel 10 having side walls 11 and a lower wall 12. A portion of the lower wall 12^a is semicylindrical in contour and the sides thereof extend upwardly within the vessel to form weirs 13 and 14 over which the pulp is adapted to pass during its travel through the apparatus. At the inlet end of the vessel 10, the side walls are united by an end wall 15 having an inlet pipe 16 leading therethrough for supplying the pulp stock to the vessel. Opposite the wall 15, another wall 17 extends upwardly into the vessel to form a weir over which the pulp flows and this wall extends downwardly beneath the lower wall 12 parallel to the wall 15 to form an inlet passage 18 through which the pulp flows upwardly over the

weir 17. A transverse wall 19 extends downwardly from the top of the vessel between the side walls 11 and terminates above the lower wall 12 in the space between the weirs 13 and 17, thus compelling the pulp to pass through an irregular path from the region adjacent the inlet conduit 16. At the discharge side of the machine the pulp flows over the weir 14 into a discharge channel which is formed between the side walls 11 by the end wall 21 and the parallel vertical wall 22 which extends downwardly from the weir 14. The discharge channel 23, thus formed, communicates through a connecting pipe 24 and an elbow 25 with the centrifugal pump 26. This pump is connected on its discharge side by pipe 27 and an elbow 28 with the channel 18 which communicates with the inlet side of the tank 10. The pump 26 thus operates to effect a local circulation of the pulp through the tank independently of the supply of pulp through the pipe 16.

In the region above the semicylindrical lower wall 12^a, there is mounted a cylindrical mold 30 having a cylindrical wall mounted on end brackets 31 provided with trunnions 32 which are journaled in bearings carried by the side walls 11. A woven wire mold 33 extends around the cylinder 30 which rotates in the direction indicated by the arrow 34. This mold 33 passes over a roll 35 and turns over a series of table rolls 36. After passing over the table rolls, the wire mold passes over a series of suction boxes 37 and then between two couch rolls 38. After passing around the lower couch roll the wire belt 33 is carried back to the cylindrical mold 30, being supported by a series of rolls 39.

The pulp stock for use in the vessel 10 is preferably formed by mixing about 5% of fibrous material with 95% water, thus forming a fluid pulp stock adapted to flow freely. This pulp stock which is introduced into the tank 10 through the pipe 16 flows through the irregular passage formed by the weirs 13 and 17 and the baffle wall 19 into the space adjacent to the mold 30. The level of the pulp stock on the inlet side of the mold member is above that on the discharge side and the liquid of the pulp stock flows through the perforated belt 33 into the interior of the cylindrical mold from which it is drawn off by pipe 40. The water

and pulp are prevented from running around the ends of the cylinder by flexible members 41 which are secured to the side walls 11 and adapted to coact with annular flanges 42 carried by brackets 31. The pipe 40 is provided with a valve 43 to permit regulation of the return of flow of the water from the interior of the cylindrical member. By regulating this valve the head of the water can be maintained within the cylindrical member below the level of the pulp stock in the vessel. The passage of the liquid portion of the pulp into the interior of the mold causes the fibrous portion to adhere to the belt, thus forming a layer or web of paper stock which is formed continuously on the belt and carried around with it. The centrifugal pump 26 causes a local circulation of pulp through the tank 10 so that the pulp moves in an angular path in the same direction that the belt 33 moves, thus facilitating the formation of the layer of pulp stock or paper web on the belt. By varying the speed of the centrifugal pump 25 and the speed of rotation of the cylindrical mold, it is possible to secure any desired effect in the formation of the paper web. The irregular path through which the pulp is compelled to flow by the arrangement of 30 the weirs 13 and 17 and the baffle wall 19 secures an even mixture of the stock and water and an even flow of the mixture over the weir 13 in the region adjacent the mold. The web which is formed while the belt is 35 passing through the stock in the tank has considerable moisture removed therefrom by the table rolls and suction boxes before it passes through the couch rolls and presses.

Although I have shown and described one 40 form of the invention for purposes of illustration, it will be understood that it may be constructed in various other ways without departing from the scope of the appended claims.

45 I claim:

1. In apparatus of the class described, a vessel for containing fluid pulp stock, a mold mounted in said vessel, a pair of conduits leading to and from said vessel, means for causing said pulp stock to flow from said vessel through one of said conduits and back through said vessel to the other of said conduits, and means for causing the pulp

stock to follow an irregular zigzag path before it reaches said mold. 55

2. In apparatus of the class described, a vessel for containing fluid pulp stock, a mold mounted in said vessel, a pair of conduits leading to and from said vessel, means for causing said pulp stock to flow from said vessel through one of said conduits and back to said vessel through the other of said conduits, a pair of weirs mounted between said last named conduits, and a baffle wall mounted between said weirs. 60 65

3. In apparatus of the class described, a vessel for containing fluid pulp stock, a mold mounted in said vessel, a pair of conduits leading to and from said vessel, means for causing said pulp stock to flow from said vessel through one of said conduits and back to said vessel through the other of said conduits, a pair of weirs mounted between said last named conduits, and a baffle wall mounted between said weirs, said baffle wall terminating above the lower wall of said vessel. 70 75

4. In apparatus of the class described, a vessel for containing fluid pulp stock, said vessel having an overflow lip on one side thereof, means for supplying fluid pulp stock to said vessel, means for withdrawing the pulp stock discharge over said overflow lip and returning the same to said vessel at the other side thereof, means for causing said pulp to flow through an irregular zigzag passage at the said other side of said vessel, and a mold mounted in said vessel between the sides thereof. 80 85

5. In apparatus of the class described, a vessel for containing fluid pulp stock, a cylindrical support mounted in said vessel, means for rotating said support, means for causing a positive movement of said pulp stock adjacent said support in the same direction in which the periphery of said support moves, an endless perforated mold passing around said support and extending upwardly out of said vessel, a series of table rolls over which said mold passes, a suction box engaging said mold for removing moisture from the pulp thereon, and a pair of couch rolls engaging said mold. 90 95 100

In testimony whereof, I have subscribed my name.

VENNING D. SIMONS.
